DESIGN FOR A SEWING MACHINE

Ramon Casas Robert, Geneva, Switzerland

Application February 20, 1937, Serial No. 67,771
In Great Britain January 27, 1937

Term of patent 14 years

To all whom it may concern:

Be it known that I, Ramon Casas Robert, a citizen of the Spanish Republic, residing at 7 Rue Gautier, Geneva, Switzerland, have invented a new, original, and ornamental Design for Sewing Machines, of which the following is a specification, reference being had to the accompanying drawings, forming part thereof.

Figure 1 is a front perspective view of the sewing machine showing my design.

Figure 2 is a rear perspective view of the sewing machine shown in Fig. 1.

Figure 3 is an end perspective view thereof.

The design is characterized by the specific shape of the head and base portion of the machine in combination with the grille embodied therein.

I claim:

The ornamental design for a sewing machine, as shown and described.

RAMON CASAS ROBERT.
